REUBEN B. DISBROW, OF MINNEAPOLIS, MINNESOTA, ASSIGNOR OF ONE-HALF TO LEVI A. DISBROW, OF OWATONNA, MINNESOTA.

OIL-BURNER.

No. 926,473.

Specification of Letters Patent. Patented June 29, 1909.

Application filed November 6, 1905. Serial No. 285,998.

To all whom it may concern:

Be it known that I, REUBEN B. DISBROW, of Minneapolis, Hennepin county, Minnesota, have invented certain Improvements in Oil-Burners, of which the following is a specification.

This invention relates to improvements in burners designed for vaporizing and burning heavy oils, and the objects I have in view are to provide a burner of this character which will be simple and inexpensive in construction, and in which the oil will be thoroughly and completely vaporized, whereby a perfect combustion of the same may be obtained and in which there will be no danger of clogging the burner.

The invention consists generally in the constructions and combinations hereinafter described and particularly pointed out in the claim.

In the accompanying drawings, Figure 1 is a side elevation of a burner embodying my invention, showing also the location of the burner in connection with a boiler and showing also the means for a preliminary heating of the oil. Fig. 2 is a longitudinal vertical section of the burner. Fig. 3 is a plan view of the same. Fig. 4 is a transverse section on line 4--4 of Fig. 2. Fig. 5 is a front end elevation. Fig. 6 is a side elevation of the conical sprayer.

In the drawings 2 represents a suitable oil pipe which may be of any suitable diameter and length. The forward end of this pipe is preferably exteriorly screw-threaded, and secured thereto is the conical block 3 which forms a sprayer as hereinafter described. This block is provided with a central opening 4 the outer end of which flares outward, forming a cone shaped mouth 5 (see Fig. 2). This block is also provided with a series of spirally arranged grooves or steam-duets 6. These grooves are arranged in the outer surface of the block and extend the full length thereof, opening at their forward ends into the conical mouth 5 of said sprayer-block. The block 3 is surrounded and inclosed by a head 7, having a conical opening into which said block fits. In the rear of the conical opening in said head is a chamber 8 and a suitable steam pipe 9, which surrounds the oil-pipe 2, is connected with the head 7 preferably by being screwed into the rear end of the chamber 8, the inner wall of said chamber and the outer wall of the pipe 9 being suitably threaded.

The rear end of the pipe 9 is provided with a coupling 10 to which is connected a suitable steam supply pipe 11. The rear portion of the oil-pipe 2 is preferably exteriorly threaded and the coupling 10 is secured to the pipe 60 by the threaded plug 12.

The rear end of the oil-pipe 2 is preferably connected to a T-shaped coupling 13, provided with the threaded plug 14 and having connected to it the oil supply pipe 15. For 65 the purpose of securing a preliminary heating of the oil, the pipe 15 has preferably a coiled portion which extends through a suitable chamber 16. This chamber is adapted to receive steam through an inlet pipe 17. Is 70 also preferably provided with a drip-cock 18.

At the outer end of the head 7 I prefer to provide a ring 19, which may be secured to said head in any suitable manner as by a screw-threaded connection (see Fig. 2) and 75 which may be locked in any desired position by a suitable set screw 20. This ring is provided with a projecting arm 21 having pivoted thereon a deflector plate 22; this plate may be adjusted to any desired angle so as 80 to deflect the flame in any desired direction. In Fig. 1 of the drawings I have shown the deflector arranged to direct the flame against the under surface of a boiler 23.

Operation: In using this burner the oil is 85 fed through the pipe 15 into the burner pipe 2. While passing through the coiled portion of the pipe 15 the oil is heated by the steam supplied to the chamber 16. The oil therefore enters the pipe 2 in a heated condition. 90 As it passes along in the pipe 2 it is subjected to further heat from the steam passing along in the surrounding pipes 9. The oil passes out of the pipe 2 and through the opening in the block 4. As it enters the conical mouth 95 5 of said block it is subjected to the several jets of steam which enter said conical mouth on spiral lines and which serve to thoroughly and completely vaporize the oil as it passes into the conical mouth of said sprayer block. The vapor as it passes out of said conical mouth is ignited and a complete combustion of the oil is secured. It will be noted that the sprayer block can be adjusted with the pipe 2 by means of the threaded plug 12. It 100 105 will also be noted that should any foreign material get into the pipe 2 the same can be readily removed without taking the burner apart by removing the threaded plug 14 and running a wire into the pipe 2 through the 110

aperture in the sprayer block 3. The oil, vapor and flame may be directed in any direction from the mouth of the burner by means of the adjustable deflector plate 22.

5 It is obvious that the preliminary heating of the oil may be secured by other means than the pipe 15 in the steam chamber 16, or in some instances the oil may be used without any preliminary heating.

10 I claim as my invention:

The combination, with an oil pipe, of a conical sprayer block having a socket to receive said pipe, said block having an aperture therethrough terminating in a conical mouth, 15 and a series of spirally arranged grooves in its outer surface opening into said mouth, a head surrounding said block and having a

conical opening to receive the conical surface of said block, and a chamber in the rear of said block communicating with said grooves, 20 a steam pipe having one end fitting into said head, and concentric with said oil pipe and spaced therefrom, a ring mounted on said head and adjustable thereon, an arm carried by said ring and a pivoted plate mounted on 25 said arm near the aperture of said block, substantially as described.

In witness whereof, I have hereunto set my hand this 31st day of October 1905.

REUBEN B. DISBROW
